DESIGN FOR A LUMINAIRE

Frederic C. Winkler and Burton A. Wyman,
Cleveland, Ohio, assignors to Westinghouse
Electric Corporation, a corporation of Pennsyl-
vania

Application April 27, 1946, Serial No. 129,005

Term of patent 14 years

(Cl. D48—23)

To all whom it may concern:

Be it known that we, Frederic C. Winkler and Burton A. Wyman, citizens of the United States, residing at Cleveland, in the county of Cuyahoga and State of Ohio, have invented a new, original, and ornamental Design for a Luminaire, of which the following is a specification, reference being had to the accompanying drawing, forming a part thereof, in which,

Fig. 1 is a perspective view of a luminaire embodying our new design, the device being symmetrical in appearance about the transverse axis through the double beaded ornamentation shown;

Fig. 2 is an end view, in elevation, of the luminaire of Fig. 1, and

Fig. 3 is a partial side view, in elevation, thereof.

We claim:

The ornamental design for a luminaire, substantially as shown and described.

FREDERIC C. WINKLER.
BURTON A. WYMAN.
